UNITED STATES PATENT OFFICE

102,790

DESIGN FOR AN ORCHESTRA STAND OR SIMILAR ARTICLE

Russell Katz, Hamilton, Ohio, assignor to Krauth & Benninghofen, Hamilton, Ohio, a firm

Application February 20, 1936, Serial No. 61,271

Term of patent 3½ years

To all whom it may concern:

Be it known that I, Russell Katz, a citizen of the United States, residing at Hamilton, in the county of Butler and State of Ohio, have invented a new, original, and ornamental Design for an Orchestra Stand, or Similar Article, of which the following is a specification, reference being had to the accompanying drawing, forming a part thereof.

Figure 1 is a perspective view of the stand, viewed from the rear side, showing my new design. Figure 2 is an end elevation thereof.

I claim:

The ornamental design for an orchestra stand, or similar article, as shown.

RUSSELL KATZ.
